SELF-LEVELLING LADDER

Jack W. Bendick, Winnipeg, Manitoba, Canada

Continuation of application Serial No. 405,424, January 21, 1954, now Patent No. 2,781,961, dated February 19, 1957. This application June 1, 1954, Serial No. 433,779

10 Claims. (Cl. 228—29)

This invention relates to a four legged structure such as stepladders, platform ladders, stairwell ladders, trestles and the like which are constructed so that the legs will automatically conform to an uneven surface within reasonable limits and thus be a self-levelling feature. The term "ladder" as used herein includes all of the foregoing devices.

This application is a continuation of my application Serial No. 405,424, filed January 21, 1954, now Patent No. 2,781,961, granted February 19, 1957, for a self-levelling stepladder as therein defined. That application described a construction in which the back legs or props and the front legs are connected together by means of a pin and slot construction to allow the front and back legs to cant or to shift angularly with respect to the front legs, the pins assuming different positions in their respective slots according to the unevenness in the floor on which the ladder is standing. Thus, by swinging one side of the back leg downwardly and toward the front of the ladder while the opposite side of the leg is moved upwardly and toward the back of the ladder, an offset in the level of the leg extremities of as much as one inch can be obtained. The front and back legs are each constructed to form a rigid unit so that they move as a unit. Therefore, the ladder levels itself at least as soon as any weight is placed upon the first step. In the said application, it will be seen that the levelling is effected by what may be termed a back and forth movement of the top end of the back leg structure relative to the front leg structure which has the effect of raising or lifting one leg of the pair of back legs and lowering the other. There will be the same relative movement of the front legs.

In the present invention, the self-levelling of the device is obtained by a lateral movement of the back leg structure from side to side relative to the front leg structure or vice versa. By the term "lateral" I mean a movement in which the back leg structure moves in a substantially horizontal plane at right angles to the back and forth movements in my said prior application. I thus obtain a tilting action of the pair of back legs which has the effect of raising one of said pair of back legs and lowering the other of said pair.

In the present application, I have illustrated several modifications of my invention as applied to a conventional stepladder but its adaptation to other structures will be obvious to those skilled in the art.

In one modification, the self-levelling ladder of the present invention comprises a pair of front legs rigidly interconnected with one another to form a rigid front leg structure, a pair of back legs rigidly interconnected with one another to form a rigid back leg structure and means including pin and slot interconnections respectively associating each leg of one pair with the corresponding leg of the other pair, the slots of said pin and slot interconnections being relatively elongated, and being angulated with respect to the plane of a floor upon which said

2

ladder is adapted to be rested when the legs are in open position. The pins of said pin and slot interconnections are slideable within said slots, thereby permitting one of said pairs of legs to tilt laterally with respect to the other of said pairs of legs in accordance with irregularities in the surface of a floor upon which said ladder is rested with its legs in open position and supplemental means for limiting the spreading apart of said pairs of legs with respect to one another.

10 For an understanding of the invention, reference is to be had to the following description which describes several embodiments of the same as illustrated in the accompanying drawings in which:

15 Figure 1 is an elevation taken from the rear, of a stepladder embodying one modification of the present invention;

Figure 2 is a fragmentary perspective view of the top portion of the ladder shown in Figure 1;

20 Figure 3 is a cross sectional view on the line 3—3 Figure 1;

Figure 4 is a fragmentary perspective view of the top end of a stepladder employing an alternative construction to that shown in Figure 1;

25 Figure 5 is a fragmentary perspective view illustrating another alternative construction;

Figure 6 is a cross sectional view on the line 6—6 Figure 5;

30 Figure 7 is a fragmentary perspective view showing the top end of a stepladder embodying still another alternative construction of the self-levelling device;

Figure 8 is a rear view of the ladder constructed in accordance with the modification illustrated in Figure 7;

35 Figure 9 is a fragmentary view, on an enlarged scale, illustrating the pin and slot interconnection shown in Figures 7 and 8;

Figure 10 is a fragmentary rear view of the top end of the ladder illustrating a further modified form of the invention;

40 Figure 11 shows an alternative construction of a cross section taken on the line 11—11 Figure 12 of an alternative construction of a leg bracket;

Figure 12 is a side elevation of the leg bracket shown in Figure 11;

45 Figure 13 is a side view of the top end of a trestle with extension illustrating the invention employed therewith;

Figure 14 is a fragmentary side view of the top portion of the trestle shown in Figure 13 taken on the line 14—14 Figure 13;

50 Figure 15 is an alternative construction of the leg bracket;

Figure 16 is a fragmentary view, on an enlarged scale, of a horn to show the notch construction.

55 Like characters of reference refer to like parts throughout the specification and drawings.

Referring first to the construction illustrated in Figures 1—3, the ladder includes a pair of parallel front uprights or legs 100, 101 which may be made of wood or metal and rigidly interconnected one with the other to form a rigid front leg structure, a pair of rear legs 102, 103 rigidly interconnected with one another to form a rigid back leg structure, brackets 104, 105 suitably mounted on and secured to the upper ends of the front legs 100, 101 respectively, a platform 106 which is supported by the brackets 104, 105. Each of the brackets 104, 105 extend rearwardly from the front leg with which it is associated and is then bent inwardly at right angles to form extensions 107, 108 respectively which underlies the rear or back edge of the platform 106.

The means by which the back legs are pivotally associated with the front legs so as to have pivotal move-

ment towards and away from the front legs to collapse the ladder and the means to permit the leg structures to tilt laterally relative to one another includes the following members. The top ends of the rear legs 102, 103 are interconnected by a cross member 109 which is pivotally connected to the top ends of the legs 102, 103 by means of pivot pins 110, only one of which is shown (Figure 3). This construction allows the back legs to pivotally move from open to close position. The slot and pin interconnection for associating the front leg structure and the back leg structure to tilt as hereinbefore mentioned, consists of angulated slots 111, 112 formed in the extensions 107, 108 and pins 113, 114 attached to the cross member 109 and slidably fitted into the slots 111, 112 respectively. The slots are arranged at an angle of between 45° to 65° to the vertical centre line of the ladder with the preferred angle being about 54°. In Figures 1 and 2 the slots 111, 112 are shown as being inclined upwardly and inwardly towards the centre line. However, the slots may incline downwardly and inwardly as illustrated in Figure 4. It will be observed that in both constructions the slots converge towards each other at the angles mentioned relative to the vertical centre line.

The back legs are maintained in a spread position at the correct angle relative to the front legs by a standard type of spreader.

Figure 1 illustrates the ladder standing on an uneven surface with the result that the front leg 101 is at a higher elevation than the front leg 100 and both the front legs are at a higher elevation than the rear legs 102, 103 respectively. The pin and slot construction hereinbefore described allows the back leg structure to tilt or rotate laterally on its horizontal axis in a clockwise or counter-clockwise direction depending on the nature of unevenness of the floor. This movement of the pair of back legs as a unit has the effect of causing the pin 113 to slide toward the top limit of the slot 111 and the pin 114 to slide toward the bottom limit of the slot 112 which has the effect of raising the leg 102 and lowering the leg 103 respectively. When the ladder has levelled itself, the movement stops. This movement is accomplished by the simple expedient of at least the application of the weight of a person stepping on the bottom step of the ladder. In some cases the weight of the ladder alone will be sufficient to cause the self-levelling action to take place.

Pivots mounted between the rear legs 102, 103 is a bucket rack 115. Placed between the side members of the rack and the back legs are wedge shaped inserts 116, 117 which are fastened to the back of the legs 102, 103, respectively, with the narrow portions pointing upwardly. The bucket rack fits between these inserts which permit the front end of the side members of the bucket rack, which are cut somewhat at an angle, to bear against the top step of the ladder.

Referring now to Figure 4, I have therein illustrated a modified construction in which the pin and slot interconnections have their positions reversed, that is the pins are carried by the brackets and the slots are formed in the cross member which is pivotally mounted on the top end of the pair of rear legs. In this modification, brackets 104a, 105a, bent inwardly to form extensions 107a, 108a respectively which are similar in construction and formation as the brackets 104, 105 with extensions 107, 108 respectively illustrated in conjunction with Figures 1 to 3 inclusive. Mounted on the top end of the rear legs 102a and 103a is a cross member 109a similar to the cross member 109. The top ends of each leg of the pair of back legs are pivotally connected to the cross member 109a by pivot pins 110a which are entered through holes 151 respectively formed in the top end of each leg and holes 152 formed in the inturned ends 153 of the member 109a. This means of pivotally connecting the back legs to the cross member 109a is the same as that shown in Figures 1, 2 and 3. The exten-

sions 107a, 108a of the brackets are formed with holes 118, 119 through which the pins 120, 121 are inserted. These pins are not movable in the slots. The cross member 109a is formed with angulated slots 111a, 112a, similar to the slots 111 and 112 and disposed at an angle within the range of angles previously described.

Referring now to Figures 5 and 6, I have therein illustrated another construction of my invention. In that construction, the ladder comprises a pair of front legs 100b and 101b which are formed into a rigid front leg structure and the pair of back legs 102b, 103b formed into a rigid back leg structure. Securely attached to the top end of the front legs 100b and 101b are a pair of brackets 122 and 123 which are turned inwardly at right angles thereto to form arms 124, 125 respectively lying immediately below the back edge of the platform 106b. Thus the brackets 122, 123 are substantially L-shaped and support the platform 106b. The rearwardly extending portions of brackets 122, 123 are each perforated for the purpose to be hereinafter explained, these perforations being identified by the numerals 126, 127 respectively. In punching the holes 126, 127, the material is not completely removed but sufficient material is left to form a flange 138 to provide a bearing surface for the back leg brackets hereinafter described with reference to Figures 5 and 6. The top ends of the pair of rear legs 102b, 103b are rigidly secured together by a cross member 128. The pin construction in the present modification for connecting the back leg structure to the brackets 122 and 123 consist of a pair of back leg brackets 129, 130 which are substantially U-shaped. The back leg brackets 129, 130 are securely attached, with the open ends down, to the cross member 128 so as to associate each leg of the back leg structure with the corresponding leg of the front leg structure. Each of the back leg brackets have an angulated portion which connect the arms of each bracket. The angulated portions of the brackets 129, 130 are identified by the numerals 131, 132 respectively and disposed at an angle corresponding with the angle of the slots previously described. The angulated portions 131, 132 are slidably fitted into the orifices 126, 127 to slide longitudinally therein. The construction just described with reference to Figures 5 and 6 permits the back leg structure to tilt exactly the same as the construction previously described in conjunction with Figures 1 to 4 and to be hereinafter described with reference to Figures 8 to 16 inclusive. In this construction there will be some slippage down the angulated portion should the weight be concentrated on one side of the ladder. Under ordinary circumstances where the weight on the ladder is more or less central there will be no slippage.

Referring now to Figures 7 to 10 inclusive, the modifications therein illustrated are basically similar to the modification illustrated in Figures 5 and 6. In this construction, the ladder comprises a pair of front legs 100c and 101c and a pair of back legs 102c and 103c, the legs of each pair being interconnected to form a rigid front leg structure and a rigid back leg structure respectively. Mounted on the top end of the front legs 100c, 101c is a pair of brackets 133, 134 respectively which extend rearwardly relative to the front leg structure. Supported by the brackets is a platform 106c. The rearward end of each of the brackets 133, 134 has a round or oval straight punched hole 136, 137 respectively so that the sides of the hole are practically at right angles, the holes being provided to receive the ends of the back leg brackets to be hereinafter described. The top ends of the legs 102c, 103c forming the back leg structure are rigidly connected together by means of a cross member 154. The pin construction for connecting the back leg structure to the brackets 133, 134 consists of a pair of back leg brackets 139, 140. These leg brackets may be shaped differently as shown in Figures 7 to 16 inclusively but each pair of leg brackets is provided with angulated horns 141,

142 respectively, the horns 141, 142 lying at the same angle and converging towards each other in the same manner as the slots hereinbefore described.

Each horn is formed with a series of notches 138 upon which the brackets 133, 134 rest. The notches may be of various shape, but in the preferred construction, the notches have a substantially horizontal surface upon which the brackets rest. This is achieved by having the notches shaped like a wide V. As will be seen by reference to Figure 16 the notches 138 are arranged in a series to simulate steps of a stair with the portion 138a representing the tread which lies substantially in a horizontal plane with the front and rear leg spread apart. The riser portion of the step, indicated by the number 138b is inclined slightly away from the vertical so as to assist the bracket sliding up and down the horn during the self adjusting process. The notches act as steps and the bracket on one side is prevented from slipping off the notch by the bracket of the other side which must ride up the horn before the first mentioned bracket slides off its notch. Once the ladder has been levelled and the brackets rest on the steps of the notches, there will be no slippage down the horn when weight is applied to one side of the ladder. In the levelling process the brackets slide up and down the respective horns until the proper notches have been reached, thus lengthening and shortening the respective legs so that the ladder will rest firmly on the uneven surface. The back leg brackets are preferably constructed from high tensile steels thereby permitting smaller dimensioned brackets to be used without detracting from their ability to withstand any and all pressures or forces that may be applied to them without bending in use. One of each of said pairs of leg brackets is secured to or mounted on the end of one of the pair forming the back leg structure. The horns 141, 142, ride in the perforations 136, 137 respectively whereby the legs work from side to side in levelling the ladder as hereinbefore described.

Figures 11, 12 and 15 illustrate an alternative construction of the leg bracket shown in Figures 7 to 10 inclusive. In each of these views only the top end of the front leg 101c which carries the bracket 134 and platform 106c, the bracket being punched to form the hole 136 therethrough for receiving the horn 141, and the top end of one of the back legs namely back leg 102c is shown. The leg bracket 139 is secured in place by bolts 155, 156. The horn 141 in the construction illustrated is also formed with notches 138 previously described to provide steps on which the bracket 134 is supported to prevent slippage down the sloping horn when the weight on the ladder is shifted from side to side as is usually the case when a person is working from the ladder. When the self-levelling device is used on heavy duty ladders, it is recommended that the free end of each horn, as illustrated with reference to the horn 141, be supported by a support plate 158 which is secured to the upper end of the leg 102c by the bolt 155, the upper end of the plate 158 being perforated to receive the free end of the horn.

Referring now to Figure 15, the support plate 158 (Figure 11) is formed integrally with the prong so that there is provided a leg bracket 139 having an angulated horn 141a formed with notches 138, the horn having a downturned extension 159 which is secured to the upper end of the leg 102c by bolt 155.

Referring now to the construction of the trestle shown in Figures 13 and 14. The trestle therein illustrated comprises a front leg unit consisting of upright legs 200, 201, connected together into a unitary rigid front leg structure by spaced apart rungs 202 and a back leg structure consisting of the upright legs 203, 204 joined into a rigid back leg structure by spaced apart rungs 205. The top end of the front and rear leg structures are joined together in the manner hereinafter described. The legs are maintained in proper spread apart position by a pair of spreaders 221, 222, the spreader 221 being connected

5 to the front and rear legs 200, 203, respectively, and the spreader 222 being connected to the front and rear legs 201, 204 respectively. Each spreader is formed of two parts pivotally connected in the centre to allow the spreader to fold when the ladder is closed.

The preferred construction for pivotally associating the front leg structure and the rear leg structure to permit the leg structures to tilt relative to one another as well as pivotally moving towards each other from open to closed position, is similar to that hereinbefore described in connection with Figures 7 to 10 inclusive with such modifications as are necessary to adapt the same to the trestle and trestle extension hereinafter described.

10 Mounted on the top end of each of the front legs 200, 201 are brackets 206, 207 respectively. Each of the brackets are similar in construction and are L-shaped so as to provide each bracket with a rearwardly extending arm 208, 209 respectively. The arms 208, 209 allow the top ends of the front back leg structure to be spaced apart sufficient to allow the extension ladder unit consisting of legs 210, 211 which are connected together into a rigid extension ladder unit by rungs 212 to be mounted so as to be slidable vertically between the top ends of the front and back leg structure. Each of the 15 arms 208, 209 are bent to form a guide channel 223 for guiding and supporting the legs 210, 211 of the extension unit the channels being completed by plates 213, 214 mounted on the upper ends of the legs 203, 204 respectively which, when the front and rear leg units are in 20 spread apart or open position, bear against the legs 210, 211 respectively to increase the vertical stability of the extension unit. Pivotally mounted on each spreader 221, 222 and positioned thereon to be in vertical alignment with the guide channels 223 are U-shaped guide members 25 224, 225 respectively. The lower end of the extension unit legs 210, 211 ride in the guide members providing vertical stability to the extension unit. This construction also allows the trestle unit to be folded for convenience in transporting.

30 The means for connecting the rear leg structure to the front leg structure will now be described. This consists of a pair of leg brackets the same as leg brackets 139, 140 mounted on the top end of the legs 203, 204 respectively. Due to the position of Figure 13, only the 35 bracket 139 on the leg 203 is visible. Consequently only the leg bracket on top of the leg 203 will be described, it being understood that the description will apply, as well, to the leg bracket on top of the leg 204. The leg bracket 139 which is mounted on the top of the leg 203 is described in relation to Figure 9, and consists of an angulated horn 141 having stepped notches 138, the horn being inserted through the hole formed in the rear end of the arm 208. This construction permits the front leg structure and the rear leg structure to tilt relative to 40 each other so as to take up unevenness in the floor level as well as allowing the front and back leg structures to be pivoted towards and away from each other to open and close position in the manner hereinbefore described. The structure for supporting the extension ladder structure 45 in an adjusted vertical position consists of supports 219, 220 which are hingedly connected to the top end of the legs 200, 201 respectively. The supports 219, 220 have their upper ends concave to form a seat for the rungs 212. The hinged supports 219, 220 move out of position 50 when raising or lowering the extension. To raise the extension, the pressure of the brackets 213, 214 is relieved by bringing the legs 203, 204 slightly in towards the front leg structure. The extension part is then raised to the desired height, after rungs 212 have passed the 55 supports 219, 220, these supports fall back into position under the rung. The legs are then spread thereby applying pressure against the extension ladder through the brackets or plates 213, 214. To lower the extension piece, the reverse procedure is adopted.

What I claim as new and desire to protect by Letters Patent of the United States is:

1. A self-levelling ladder comprising a pair of front legs permanently connected together forming a rigid front leg unit, a pair of back legs permanently connected together to form a rigid back leg unit and complementary parts including pin and slot interconnections respectively associating each leg of one pair with the corresponding leg of the other pair, the parts of said pin and slot interconnections being slidable relative to each other, and one part being angulated with respect to the plane of a floor upon which said ladder is adapted to be rested when the legs are in open position and in a direction to permit one of said leg units to have limited rotative movement in a lateral direction relative to the other leg unit to automatically change the elevation of one leg of one unit relative to the other legs of the ladder whereby the four legs of the ladder automatically adjust themselves to an uneven floor surface and automatically lock in the adjusted position when said ladder is under load with its legs in open position, and supplemental means for limiting the spreading apart of said pairs of legs with respect to one another.

2. A self-levelling ladder according to claim 1 the additional feature of an extension ladder unit mounted perpendicularly between the front and rear leg units, and means carried by the said brackets and the spreaders for maintaining the extension in a perpendicular position, and hinged members mounted on the top of each leg of the front leg unit, said members engaging with a rung of said extension ladder unit thereby supporting said unit at a predetermined height.

3. A self-levelling trestle comprising a pair of front legs interconnected to form a rigid front leg structure, a pair of rear legs interconnected to form a rigid rear leg structure, a bracket having a rearwardly extending arm mounted on the top end of each front leg, each arm having perforations at the rear end thereof, a leg bracket mounted on the top end of each rear leg, each leg bracket having an angulated horn slidably fitted into the perforation of the adjacent arm, two of said brackets with related horns forming a pair, the horns of the pair being disposed at an angle of between 45° and 65° to the vertical centre line of the ladder when in open position, the said horns converging towards each other, a series of step-like notches formed in the upper surface of each horn, and a spreader connecting the front and rear leg units to prevent the legs spreading beyond a predetermined limit.

4. A self-levelling trestle according to claim 3 the additional feature of an extension ladder unit mounted perpendicularly between the front and rear leg units, and means carried by the said brackets and the spreaders for maintaining the extension in a perpendicular position, and hinged members mounted on the top of each leg of the front leg unit, said members engaging with a rung of said extension ladder unit thereby supporting said unit at a predetermined height.

5. A self-levelling ladder comprising a pair of front legs permanently connected together forming a rigid front leg unit, a pair of rear legs permanently connected together forming a rigid back leg structure, means interconnecting the back and front leg structures at the upper ends thereof to permit the leg structure to have limited rotative movement in a lateral direction to automatically tilt laterally relative to one another in addition to the pivotal movement of the leg structures towards and away from each other, said means including a connecting member associating each leg of one pair with the corresponding leg of the other pair comprising complementary parts, one part being a slot and the other part being a pin slidably mounted in said slot, one of said parts being angularly disposed relative to the other part and being angulated with respect to the plane of the floor upon which said ladder is adapted to rest when the

legs are in open position, said pin being slidable in said slot to have relative movement with respect thereto in accordance with the irregularities in the surface of the floor upon which the ladder is standing with the legs in spread apart position to automatically change the elevation of one leg of one unit relative to the other leg unit of the ladder whereby the four legs of the ladder automatically adjust themselves to an uneven floor surface and automatically lock in the adjusted position when said ladder is under load and a spreader connecting the front and back legs to prevent the legs spreading beyond a predetermined limit.

6. A self-levelling ladder comprising a pair of front legs permanently connected together forming a rigid front leg unit, a pair of rear legs permanently connected together to form a rigid back leg structure, means interconnecting the back leg unit and front leg unit at the upper ends thereof to permit the leg structures to automatically tilt laterally relative to one another in addition to the pivotal movement of the leg structures towards and away from each other, said means including a connecting member associating each leg of one unit with the corresponding leg of the other unit, said connecting members comprising complementary parts, one part being a bracket and the other part being a pin slidably mounted in said bracket, said pin being angularly disposed relative to the bracket and being angulated in a direction with respect to the plane of the floor upon which said ladder is adapted to rest when the legs are in open position to permit the leg units to tilt laterally relative to one another, whereby the four legs of the ladder automatically adjust themselves to an uneven floor and automatically lock in the adjusted position when said ladder is under load, and a spreader connecting the front and back legs to prevent the legs spreading beyond a predetermined limit.

7. A self-levelling ladder according to claim 6 in which the bracket is associated with and extended rearwardly from the legs constituting one of the leg units, the rearward extension of the bracket having an orifice to receive the angularly disposed pin associated with the corresponding leg of the other leg structure.

8. A self-levelling ladder comprising a pair of front legs, the legs in said pair being permanently connected together to form a rigid front leg unit, a pair of back legs permanently connected together to form a back leg unit, and means including pin and slot interconnections respectively associating each leg of one unit with the corresponding leg of the other unit, the pins of said pin and slot interconnections being relatively elongated, and being angulated with respect to the plane of a floor upon which said ladder is adapted to be rested, when the legs are in open position, the pins of said pin and slot interconnections being slidable within said slots thereby permitting one of said leg units to tilt laterally with respect to the other of said leg unit in accordance with irregularities in the surface of a floor upon which said ladder is rested with its legs in open position, whereby the four legs of the two units automatically adjust themselves to the said irregularities and automatically lock in the adjusted position during the time the said ladder is under load, and supplemental means for limiting the spreading apart of said pairs of legs with respect to one another.

9. A self-levelling ladder according to claim 8 in which each pin has a series of step-like notches formed in its upper surface, said pin being disposed at an angle of between 45° and 65° to the vertical centre line of the ladder when in open position to cause one bracket to slide up the pin with which it is associated and the other bracket to slide down its pin until each bracket is supported on the notches with the bottom end of each leg resting firmly upon the floor.

10. A self-levelling ladder according to claim 8 in which the said horns converge towards each other, the upper ends being closer to each other than the lower ends.
